MACHINE FOR MAKING NUT LOCKS, &c.

No. 274,251.

Patented Mar. 20, 1883.

UNITED STATES PATENT OFFICE.

HARRY W. ARMSTRONG, OF VERONA, ASSIGNOR TO METCALF, PAUL & CO.,
OF PITTSBURG, PENNSYLVANIA.

MACHINE FOR MAKING NUT-LOCKS, &c.

SPECIFICATION forming part of Letters Patent No. 274,251, dated March 20, 1883.
Application filed August 16, 1882. (No model.)

To all whom it may concern:

Be it known that I, HARRY W. ARMSTRONG, of Verona, in the county of Allegheny and State of Pennsylvania, have invented a new and useful improvement in machines for forming annular nut-locks and giving them a spiral or corrugated or twisted shape, as may be desired; and I do hereby declare the following to be a full, clear, and exact description thereof.

10 My machine is designed as an improvement in machines for making spiral washers for nut-locks described in Letters Patent No. 159,932, to Metcalf, Paul & Co., assignees of Samuel Trethewey, dated January 29, 1875, and in Letters Patent No. 175,854 to W. Metcalf, dated March 28, 1876. Those machines are capable of making spring-washers and giving them the desired set or spiral shape, with or without a twist, and have been so used; and my im-
15 proved machine, while operating on the same general principle and employing many of the devices described in the machines referred to, is designed to simplify the construction and operation of the machine, and especially in the manufacture of twisted annular nut-locks to give greater regularity and any required degree of twist.

To enable others skilled in the art to make practical use of my invention, I will describe 30 the construction and operation of my machine, referring to the accompanying drawings, forming part of my specification and consisting of nine figures.

Figure I is a front elevation of my machine. 35 Fig. II is a transverse vertical section through the line $x-x$ of Fig. I. Fig. III is a longitudinal vertical section of Fig. I. Figs. IV, V, VI, VII are representations of various details. Figs. VIII and IX are a plan view and section of 40 one of the forms of nut-locks which my machine is capable of making.

Like letters of reference denote the same parts in the several figures.

In the drawings, A is the bed-plate of the 45 machine, supported by a suitable frame. The horizontal power-shaft B, having its bearing in the frame of the machine under the bed-plate, carries two cog-wheels, a a' . The cog-wheel b is carried by the revolving die-holder E, which serves as its shaft, and is attached to the die-holder with a spline or feather, so as to permit of a slight longitudinal motion of the die-holder E, in addition to its rotary mo-

tion. The cog-wheel b' , near the other end of the machine, is carried by the die-holder E', and may be keyed thereto without a feather, as the die-holder E' does not have any longitudinal motion when the machine is in operation. The die-holders E and E' are in the same axial line parallel to the main shaft B, and each is supported in a journal-box, D D', by posts d d' on the bed-plate A. The cog-wheels a and a' are of equal diameter, as also are the cog-wheels b and b' , so that the die-holders E and E' revolve at the same speed and in the same direction. A collar, c, on the die-holder E serves as a bearing for a spiral spring, x, which also bears against the end of the journal-box D, and thus retracts the die-holder E and its die, and keeps them in that position (shown in Fig. I) until forced forward by a cam, as hereinafter described, to the position shown in Fig. III.

The dies C C' are very similar to those used in the Trethewey machine before referred to, and are screwed into a suitable cavity in their respective die-holders. These dies are made as shown in section in Fig. III, the die C being tubular, so as to receive the end of the mandrel I, and the counter-die C' being a sleeve-die, so that the mandrel I may pass through it. Each of these sides C C' has a collar, h h' , which, when the dies are screwed into their respective die-holders, rests against the outer extremity of the die-holder, thus preventing any strain on the screw-threads of the dies and die-holders. The die-holder E' also has a collar, r, which bears against the face of the journal-box D', so as to cause the strain of the pressure of the swaging-die C, when the nut-lock is being swaged, to be borne by the journal-box D' and its standard d'. As in the Trethewey machine, the two dies serve to seize and hold the blank to be operated upon, and in my machine they also give to it the required facial conformation, as either spiral or corrugated, or both spiral and corrugated, as may be desired. The shape thus given to the nut-lock (in addition to its annular shape) will depend on the contour of the face of the dies, which are made counter-parts of each other, so that if a simple spiral shape is desired the die shown in the Trethewey patent will be used; if a spiral shape, with the ends of the nut-lock turned out of the regular line of helix, then the die shown in the Metcalf patent will be employed, a counterpart

die being added; and if a nut-lock is to be made having a corrugated shape—such, for example, as that shown in the Patent No. 236,634, to Daniel R. Pratt—the faces of the dies will require to be so shaped, as shown in Figs. VIII and IX of the drawings attached to this specification, one special advantage of my machine being that I am enabled to make annular washers of various shapes by a mere change of the dies, without other alteration in the machine.

Within the counter-die C' is placed a mandrel, I, (as in the prior machines before referred to,) the forward extremity of which projects far enough beyond the face of the die C' to enter the cavity of the die C, made for that purpose, when the nut-lock is to be formed. The rear portion of the mandrel I within the die-holder is square in cross-section, as is also that portion of the cavity of the die-holder through which the square part of the mandrel passes, so as to cause the mandrel I to revolve with the die-holder E'. When the nut-lock is being formed around the mandrel I the mandrel projects forward through the counter-die C' sufficiently to enter the cavity of the swaging-die C when the latter is advanced to the position shown in Fig. III. The mandrel remains in this advanced position until the nut-lock is finished, and is ready to be delivered from the machine. To effect this, when the swaging-die C recedes, or immediately thereafter, the mandrel I is retracted until its point is inside of the counter-die C', thereby stripping the nut-lock from the mandrel, and permitting it to fall away from the machine. This motion of the mandrel is effected as follows: The mandrel I extends horizontally backward through the revolving die-holder E', and through a standard, j, attached to the bed-plate A, and passes through a sleeve, g, to which it is attached, and in which its position is adjusted by a set-screw, s". Around the mandrel I, and between the sleeve g and the standard j, is a spiral spring, x', which causes the retraction of the mandrel at the proper time. Except when thus retracted to deliver the finished nut-lock, the mandrel is retained in its advanced position, as in Figs. I and III, by means of a face cam, K, attached to the extremity of the main shaft B, and revolving therewith. A lever-arm, l, pivoted at y to a bracket projecting from the bed-plate A, is pivoted at its upper end (the extremity of its longer arm) to the sleeve g, while the short arm of the lever l carries at its extremity a roller, z, which is pressed by means of the spring x' against the outer face of the cam K, near its circumference. The operative face of the cam K is a plane surface excepting at one point where there is a recess, k, of sufficient length to permit the roller z to enter it, and of sufficient depth to give motion enough to the lever l to permit the spring x' to force back the mandrel I. The construction and operation of this device are shown in Fig. III.

In Fig. I the die C is represented as retracted from its counter-die C', which retraction is

effected by the spiral spring x, as before stated but when the blank is to be operated upon, as it has not only to grip the blank while it is wound around the mandrel I, but also to give to it the spiral or corrugated shape, it becomes necessary that a swaging action should be communicated to the dies as well as a mere gripping action. For this purpose a device is used. (Shown in Figs. III and IV.) A collar, e, is formed on the die-holder E, (or preferably attached thereto by a countersunk screw, v,) which, when the die-holder E and swaging-die C are retracted, comes in contact with the face of the journal-box D. This collar e partially enters a sleeve, f, adjustably attached by set-screw t to the forward end of the journal-box D, so that the sleeve f is stationary while the die-holder E and its collar e revolve. A cam or tooth, i, projects from the circumference of the collar e of the die-holder, such tooth being beveled on one side or face only, as shown in Fig. III. A corresponding notch or depression, i', is made in the otherwise plane surface of the face of the sleeve f, the beveled side of the tooth i facing toward the direction in which the die-holder revolves. Now, if the tooth i is entered into the notch i' of the stationary sleeve f, as in Fig. I, the die C is retracted; but as the die-holder E revolves the beveled face of the tooth i rides over the beveled surface of the notch i' in the collar and passes out of the notch, and thereby forces the die-holder E and its die C forward toward the counter-die C' against the resistance of the spring x, as shown in Fig. III, and preserves it in that position until the tooth i again reaches the notch i' in the sleeve, into which it drops, being forced back by the spring x, thus causing the die C to recede to the position occupied by the dies when the blank is fed into the machine, which is represented in Fig. I. This occurs once in each revolution of the dies and mandrel.

On the side of the journal-box D is a tapped lug, q, through which passes a set-screw, s, the point of which bears against the rear face of the sleeve f, so that when the adjusting-screw t in the sleeve f is loosened the position of the sleeve on the journal-box D may be nicely adjusted to regulate the position of the die-holder E and swaging-die C relatively to the counter-die C', and thereby, also, the width of space between the faces of the dies C and C' when the swaging-die C is advanced to grip the blank. When the sleeve f is properly adjusted the screw t is tightened to hold it firmly in position. A screw, s', passing through a tapped lug, q', on the journal-box D', presses more or less against the hub of the cog-wheel b' of the die-holder E'. The object of this is to act as a brake on the cog-wheel b', so as to insure steadiness of motion by the friction of the point of the screw s' against the end of the hub. A similar screw and lug may be used, also, on the opposite side of the journal-box D', so as to prevent the cog-wheel b' from being put out of its proper position.

In order to insure the winding of the blank

around the mandrel, which would otherwise be difficult or impossible where the nut-lock is to be made of corrugated shape, and the swaging-dies form, together with the mandrel, 5 the cavity in which the nut-lock is to be shaped, I employ a loose roller, R, which is set in a frame, G, attached to the bed-plate of the machine, the periphery of the roller R just touching the surface of the revolving dies C C', and 10 revolved only by frictional contact therewith or with the blank which is being formed by the machine. The roller-frame G overhangs the dies and mandrel, as shown in Fig. II, and the roller may be made to press with greater or 15 less force on the dies or on the blank being rolled between them by means of a screw and nuts n' n'' on the roller-shaft, Figs. I and II.

In front of the dies, and in the line of the cavity formed by them and of the bite of the 20 mandrel I and roller R, is a feeding-box, F, the cavity of which is of the shape of the cross-section of the blank of steel from which the nut-lock is to be formed. This feed-box F is set in a journal-box, H, supported by a post, h, attached to the bed-plate of the machine, and, excepting in cases where it is desired to 25 twist the nut-blank as it is being fed into the machine, the feed-box should be stationary. If, however, it is desired to make a twisted 30 nut-lock, the nut-blank is revolved, thereby twisting the blank, the forward end of which is held fast between the dies C C' of the machine. The revolution of the feed-box is effected by means of a bevel cog-wheel, m, keyed 35 onto the revolving die-holder E, which gears into a beveled pinion, n, keyed into the front end of the feed-box F. The relative size of the cog-wheel m and pinion n regulates the 40 number of twists given to the nut-blank. When the nut-blank is not to be twisted the pinion n is unshipped and removed from the machine and the feed-box is secured from rotation and in its proper position by a set-screw, t', in the 45 journal-box H.

45 In Figs. I and III of the drawings the feed-box is not represented, as it occupies a position in the machine in front of dies and feed-roll, and it cannot be shown without obscuring the feed-roller and dies. The beveled-gear wheels m and n, by which the feed-box is 50 rotated, are also omitted in Figs. I and III, for the reason that they are not necessary to the operation of the machine when the blank is not to be twisted. They are represented, however, in Fig. II.

55 As it is not requisite even in making twisted nut-locks that the blank should receive a uniform and continuous twisting motion, such as would be communicated by the beveled-gear 60 wheels m n, a simple and inexpensive device may be substituted for the gear-wheels, consisting of four radial arms projecting at right angles to each other from the circumference of the die-holder E and four similar radial arms 65 projecting at right angles to each other from the feed-box F, these arms being of such length and so arranged as that on the revolution of

die-holder E its arms will successively engage the corresponding arms on the feed-box, and thus cause the rotation of the feed-box on its 70 axis. These arms or the beveled cog-wheel m may be attached to either of the die-holders E or E', as may be more convenient. The rear extremity of the feed-box next to the dies is reduced in diameter with a curving contour, 75 so as to extend the feed-box as near to the bite of the roll and mandrel as may be without actual contact. A side view of the feed-box removed from its bearing is shown in Fig. IV, and an end view in Fig. V.

80 The operation of my machine is as follows: When the parts are in the position shown in Fig. I the nut-blank, which is a piece of steel of the required length and shape in cross-section, having been first heated to a welding-heat, 85 or nearly so, is inserted into the feed-box until its forward end rests on the upper surface of the mandrel I and touches the face of the counter-die C'. The die C then advances and seizes the nut-blank, the opposite faces of dies 90 C C' forming, with the mandrel I, a groove, into which the nut-lock blank is to be rolled, the parts then occupying the position shown in Fig. III. As the dies revolve the roller R forces the nut-blank into the cavity and compels it to assume the required shape. When a single revolution of the dies is complete the cam-tooth i on the holder E enters the cavity i' in the collar f, and allows the die C to be withdrawn by the spring x, and simultaneously 100 the mandrel I is withdrawn into the die C' by the spring x', thus stripping the finished nut-lock off the mandrel I, when it drops to the ground, and the machine is again in position for the repetition of the operation. As before 105 stated, the nut-blank having been seized at its forward end between the dies C C' is twisted, as it enters the machine, by the revolution of the feed-box, if the pinion n is in place; but if not, the nut-lock is formed without being 110 twisted.

115 By my machine nut-locks may be made of round or square steel, or of steel of any other desired shape in cross-section.

What I claim as my invention, and desire to 115 secure by Letters Patent, in machines for forming annular nut-locks, is—

1. The combination of a gripping-die, a counter-die, a mandrel, and an adjustable loose pressure-roller for rolling and swaging blanks 120 of steel into annuli of spiral, corrugated, or other desired shape, arranged and operating substantially as described.

2. The combination of a revolving feed-box with a pair of swaging-dies and mandrel, constructed and arranged substantially as and for 125 the purpose set forth.

In testimony whereof I have hereunto set my hand this 12th day of August, A. D. 1882.

HARRY W. ARMSTRONG.
